No. 892,602.

PATENTED JULY 7, 1908.

J. W. LUNDGREN,
MATCH MAKING MACHINE.
APPLICATION FILED AUG. 17, 1906.

FIG. 1

UNITED STATES PATENT OFFICE.

JOHN W. LUNDGREN, OF DULUTH, MINNESOTA.

MATCH-MAKING MACHINE.

No. 892,602.

Specification of Letters Patent.

Patented July 7, 1908.

Application filed August 17, 1906. Serial No. 330,978.

To all whom it may concern:

Be it known that I, JOHN W. LUNDGREN, a citizen of the United States, residing at Duluth, in the county of St. Louis and State of Minnesota, have invented certain new and useful Improvements in Match-Making Machines; and I do hereby declare the following to be a full, clear, and exact description of the invention, such as will enable others skilled in the art to which it appertains to make and use the same.

My invention relates to match making machines and has for its object the provision of means for retarding the splint-receiving belt at the line of transfer of the splints from the cutter-head to the belt. The purpose of this is to draw or hold the splint-receiving link, at that line, back against the propelling faces of the gear-teeth which would normally drive it, and so take up the wear and steady the link, and also to hold said link up against the face of the driving wheels and against a fixed central abutment so that there will be practically no yielding of the link when the splints are thrust into it, and the tendency for the link to spring or yield when the cutter head draws away from the splints will be greatly diminished.

With these and other objects in view, it consists of the constructions, combinations and arrangements of parts hereinafter described and claimed.

In the accompanying drawings, Figure 1, is a fragmentary front elevation of a match making machine, omitting the match and splint carrying belt: Fig. 2, is a perspective view of one link of a match and splint carrying belt and of the link retarding and upholding device which the link has passed over. Fig. 3, is a central vertical longitudinal sectional view of the tongue B of said retarding and upholding device.

My invention may perhaps be applied to various match making machines but is especially applicable to the improvement of the machine disclosed by Letters Patent of the United States dated the 22nd day of August 1905, No. 797697, issued to John W. Lundgren and Alfred J. Bell, jointly, for match making machines.

In the herewith accompanying drawings, 1, is a fragment of a supporting frame embodying angle iron ways 1^a. Mounted on said frame is a rotatable shaft 2. Keyed to said shaft are sprocket wheels 3; 3, which engage a conveyer belt embodying bars 6

(some of which are removed to better disclose other parts), having splint receiving apertures 6^a formed therein, and eyes 6^b attached thereto for engaging the teeth of 60 said sprocket wheels, which wheels are adapted to drive said belt. Mounted on said shaft 2 is a worm gear 4 for driving said shaft, said gear being driven by a worm 4^a carried by a shaft 4^b, which may be driven by any suitable means (not shown) well known to the art. Secured to said frame in any suitable manner in rear of said sprocket wheels and extending forwardly between said sprocket wheels is a horizontally disposed fixed abutment plate 5, the lower face of which is on the horizontal plane of the lower faces of said sprocket wheels, said abutment extending at its forward end only a short distance forward of central vertical plane of the axis 75 of rotation of said sprocket wheels. Secured to said frame forward of said sprocket wheels are abutment guides 1^b, 1^b, between which and the sprocket wheels, the conveyer belt passes downward and thence backward 80 below said abutment 5 and said belt being in its downward and backward course engaged by the teeth of said sprocket wheels. Secured to said angle irons is a plate preferably comprising the body portion A and the 85 rearwardly extending arms B, C, and D, which plate extends below the conveyer belt, which at that point travels rearwardly between said plate and said abutment 5. Mounted on said plate are spring supported 90 fingers 8, 9 and 10 adapted to yieldingly bear against the lower faces of the successive bars of said belt on the line of delivery of splints to said belt (which line is parallel with the axis of rotation of said sprocket 95 wheels and in the same vertical plane therewith), and to hold back the bars on that line and against the driving faces of the sprocket teeth, to take up the wear. Said fingers are also designed to hold said links up against 100 the faces of said sprocket teeth and to prevent or reduce the tendency of the links to buckle downward when the cutter knives (not shown, but well known to the art) are being withdrawn from the splints which 105 have been thrust upwardly by them into the conveyer belt bars. E and F are tension wheels which engage said conveyer belt at the point where it turns to pass downwardly in front of the machine. Said belt extends 110 rearwardly and is engaged at its rearward loop by idler wheels (not shown, but well

known to the art). Forwardly directed punches represented by dots 7 are mounted in a horizontally reciprocating punch carriage 7^a and are adapted in the manner well known to the art to eject the finished matches forwardly from a filled bar of the conveyer belt at the same time that the vertically reciprocating cutter head (not shown, but well known to the art) thrusts upward a series of 10 splints into an empty bar of said belt.

What I claim is,

1. In a match making machine, the combination of a frame, a splint receiving link, means for driving said link across the line at 15 which it receives splints, means for punching said splints out of said link after said splints have been embodied in finished matches, yielding link-retarding-and-supporting means adapted to bear up against 20 said link after it has passed the punching out means and before it has passed the line at which it receives splints.
2. In a match making machine the com-

binaton of a frame, a splint receiving link, means for driving said link across the line at 25 which it receives splints, means for punching said splints out of said link after they have been embodied in finished matches, downwardly yielding means adapted to bear against the lower face of said link after it has 30 passed the punching out means and while it is passing the line at which it receives splints.

3. In a match making machine, the combination of a frame, a splint receiving link, 35 means for driving said link across a line at which it receives splints, spring fingers adapted to bear up against the splint receiving side of said link while it is passing said line.

In testimony whereof I hereunto affix my signature, in presence of two witnesses.

JOHN W. LUNDGREN.

Witnesses:

JAMES T. WATSON,
WILLIAM J. STEVENSON.
